UNITED STATES PATENT OFFICE.

GEORGE T. LEMELIN, OF SPRINGFIELD, MASSACHUSETTS.

BACK-FOLDER FOR ENVELOP-MACHINES.

SPECIFICATION forming part of Letters Patent No. 738,553, dated September 8, 1903.

Application filed July 21, 1902. Serial No. 116,330. (No model.)

To all whom it may concern:

Be it known that I, GEORGE T. LEMELIN, a citizen of the United States, residing at Springfield, in the county of Hampden and 5 Commonwealth of Massachusetts, have invented a new and useful Back-Folder for Envelop-Machines, of which the following is a specification.

My invention relates to improvements in envelop-machine folders for turning down and sticking one of the large flaps to the side flaps of the envelop-blank, in which a folder-plate of peculiar construction and yielding bearings for the plate are employed, as herein- 10 after fully described, and especially claimed; and the objects of my improvement are to provide means for rolling over rather than abruptly bending the rear edge of the envelop-blank, for holding the envelop-blank 15 so that all of the edges are folded evenly, and for pressing down the rear flap, also means for preventing injury to the folder or other parts in case a bunch of envelops, a nut, or other obstruction accidentally gets between 20 the folder and trap.

With my device I am able to produce envelops which have more uniform edges than has been done heretofore and to avoid crushing the edge operated on by the folder-plate.

30 I attain these objects by the means illustrated in the accompanying drawings, in which—

Figure 1 is a front view of my folder; Fig. 2, a plan view of said holder; Fig. 3, a side view of one of the yielding bearings mounted on a table, showing in dotted lines the position it would assume if an obstruction got under the folder-plate; Fig. 4, a vertical cross-section through the folder-plate; and Fig. 5, 35 a side view of the device mounted on a table and of rock-shaft connections, the folder-plate being shown by dotted lines in its forward position.

Similar letters refer to similar parts throughout the several views.

The folder-plate *a* is of ordinary construction except at the bottom, where it is provided with a roll *b*, extending the whole length of the plate and let into the table *c* when in 40 position. The front portion of the roll *b* extends forward considerably beyond the face of the plate *a*, so as to permit the plate to

rest upon the trap *c'* when thrown forward. Lugs *d* project from the back of the plate *a*, and journals *e e* project from the ends of the 55 roll *b*.

From the foregoing description of the folder-plate it will be readily seen that when said plate is swung forward and downward from the normal upright position it catches the 60 adjacent flap portion of an envelop-blank previously deposited in its path, quickly turns it down, and rolls over the adjacent edge instead of crushing it, as does the old style of folder-plate. A plate of this descrip- 65 tion also holds the blank in place and insures an even fold to all of the edges, the reason for which is because of the peculiar rolled construction of the base and the straight face of the plate, which rises in un- 70 broken line from the roll *b*. Envelops folded by this means are of uniform size, correspond- 75 ing edges being even, which is not the case when the blank is not held firmly at the beginning of the folding operation by the 80 folders, and, as before stated, the rolling action produced by the plate *a* is not such as to crush the paper at this point; but an edge is formed which is literally rolled over. The 85 roll in the paper is necessarily slight, nevertheless is not a crushed bend. This feature of my invention can be used either with or without the yielding bearings described below, and the latter may be employed with other kinds of folder-plates.

It will be understood that there are two bearings for each folder, and a description of one is applicable to the other.

A holder *f* is provided with a bolt-hole *g*, preferably elongated laterally for adjustment, a pin *h* rising from the top and lugs *i i* at the front end. A journal-block *j*, perforated laterally at the front at *j'* to receive one of the journals *e*, has a tongue *k*, adapted to enter between the holder-lugs *i*, to which 95 it is pivoted by a pin *l*, extending through horizontal holes in said tongue and lugs. Any other suitable joint may be used at this point; but the one just described is strong and rigid and for this reason desirable. The 100 hole *j'* is below the horizontal center of the block *j* in order to allow the bottom of the roll *b* to extend below the top surface of the table *c* when said block is in place on the ta-

ble and the plate *a* is connected therewith. A stiff flat spring *m*, provided with a bolt-hole similar to the hole *g* and another hole to receive the pin *h*, is adapted to be placed on 5 and secured to the holder *f* when the same is fastened to the top of the table *c* by means of a bolt *n*. The front or free terminal of the spring *m* reaches over onto the top of the block *j* and presses the same downward onto 10 the table with sufficient force to hold the plate *a* in place with all the power required for ordinary purposes, yet the spring is not so strong as to prevent the raising of the block *j* when an obstruction gets beneath 15 said plate in its downward sweep. The pin *n* serves simply to assist in retaining the spring *m* in position.

As before stated, two yielding bearings are used, one at each end of the folder-plate, and 20 they are securely bolted to the table. These yielding bearings hold the folder-plate securely in position, permitting the same to swing for the performance of its work; but at the same time they will yield or give sufficiently to permit one or both ends of said 25 plate to be elevated and thus avoid breakage when the plate is subjected to undue strain.

A link *o* is pivoted at one end to the lugs 30 *d* on the back of the plate *a* and at the other end to the rocker-arm *p*. The rocker-arm *p* is carried by a rock-shaft *q*, journaled beneath the table *c*.

There is nothing new about the mechanism 35 which operates the folder, and it is to be understood that the rock-shaft *q* is actuated in the usual manner through the medium of a suitable cam on the main shaft of the machine and a connecting rod and arm, all well-known parts in the art, which it is not deemed necessary to show or further describe.

Should the blocks *j* be elevated against the resiliency of the springs *m* by reason of some 45 obstruction with which the plate *a* comes in contact, no impediment is thrown in the way of the further operation of said plate. On the contrary, the cycle of such operation may be completed or even repeated before the machine is stopped without any resulting damage. Without yielding bearings for the 50 folder-plate or other equivalent means result above noted would not be possible of attainment.

Minor changes in construction aside from 55 those already alluded to may be made without departing from the nature of my invention.

What I claim as my invention, and desire to secure by Letters Patent, is—

60 1. The combination in an envelop-machine of a back-folder having journals, and yielding boxes in which said journals are mounted.

2. The combination with a back-folder plate for envelop-machines provided with journals at the ends, of a holder having blocks for said 65 journals, pivotally connected with said holder, and resilient means for normally retaining said blocks in place on the machine-table.

3. The combination, in an envelop-machine, 70 with a back-folder plate provided with journals, of holders rigidly attached to the machine-table, blocks for the plate-journals, pivotally connected to said holders, and springs arranged to normally retain said blocks in place, substantially as set forth.

4. The combination, in an envelop-machine, with a back-folder provided with journals, of holders having springs thereon bolted to the machine-table, and blocks for the plate-journals, pivotally connected to said holders, the 80 free ends of said springs bearing on the blocks, for the purpose set forth.

5. The combination, in an envelop-machine, 85 of a back-folder, provided with journals, a pivotally-connected holder and block for each of the plate-journals, springs arranged to normally depress said blocks, and means for operating the plate in its bearings, substantially as set forth.

6. The combination, in an envelop-machine, 90 with a back-folder plate provided with a roll extending in an unbroken curve from and beyond the face of said plate, around the base thereof, and journals projecting from the ends of said roll, of pivotally-connected holders 95 and blocks for said journals, and springs arranged to normally depress said blocks, substantially as set forth.

7. A bearing for envelop-machine back-folders plates, comprising a holder *f* and a superimposed flat spring *m* both bolted to the machine-table, and a journal-block *j* pivoted at *l* to said holder, the free end of said spring being arranged to bear upon and press down the block, substantially as shown and described.

8. The combination, in an envelop-machine, 100 of a back-folder plate provided with a roll extending in an unbroken curve from and beyond the face of said plate, around the base thereof, journals projecting from the ends of 105 said roll, pivotally-connected holders and blocks for said journals, springs arranged to normally depress said blocks, and means for operating the plate in its bearings, substantially as set forth.

In testimony whereof I have signed this specification in the presence of two subscribing witnesses.

GEORGE T. LEMELIN.
